ELECTRIC CONTROL CIRCUIT

Charles J. Sperr, Jr., Beloit, Wis., assignor to Warner Electric Brake & Clutch Company, Beloit, Wis., a corporation of Wisconsin

Application March 11, 1955, Serial No. 493,655

6 Claims. (Cl. 307—137)

This invention relates to an electric control circuit in which the voltage of a source is applied to a load device through two or more sets of switch contacts connected in series with the device. More particularly, the invention relates to such a circuit which is subjected to conditions giving rise to separation of the switch contacts by foreign matter and, consequently, to failure of the circuit to be completed for energization of the load device when desired.

The general object of the invention is to insure reliable operation of circuits of the above character and avoid the difficulties resulting from accumulation of foreign matter on the switch contacts by a novel arrangement of circuit elements which utilizes the voltage of the source to break down such foreign matter without affecting normal operation of the circuit.

A more detailed object is to provide a novel arrangement of impedance elements for applying across each of the sets of contacts separated by foreign matter substantially all of the voltage of the source or a part thereof sufficient to break down the film.

Other objects and advantages of the invention will become apparent from the following detailed description taken in connection with the accompanying drawings, in which

Figures 1, 2, and 3 are schematic wiring diagrams showing different operating conditions of a preferred control circuit embodying the novel features of the present invention.

Fig. 4 is a schematic wiring diagram of a modified circuit.

The present invention is particularly adapted for use in electrical control circuits in which the voltage of a source 10 is applied to a load 11 through the contacts of two or more switches 12, 13 and 14 connected in series with the load and the source. The load may be any current responsive device such as a relay coil which is energized when the current supplied by the source reached a predetermined level. While the switches may be of different types, each is shown in the present instance as a single pole single throw switch having a movable contact and a fixed contact. Under some operating conditions, circuits of the above character are subject to unreliable operation due to collection on the contacts of one or more of the switches of dust or other foreign matter which prevents closure of the switch and completion of the energizing circuit for the load.

To overcome the foregoing difficulty when operation of two or more of the switches 12, 13 and 14 becomes faulty due to foreign matter on the switch contacts, the present invention contemplates the provision of novel means for selecting the faulty contacts and applying only to such contacts voltage of the source for breaking down the foreign matter. This means comprises impedance elements 15 and 16 which are connected individually in shunt around at least all except one of the switches. Each element has characteristics such that, when the full voltage of the source 10 is applied to the element and the

2

load in series, the current flow in the load is less than the predetermined value necessary for its energization and the voltage drop across the impedance element is equal substantially to the full voltage of the source. The load then remains deenergized and the voltage across the impedance element is available to break down any foreign matter which is separating the contacts of the switch shunted by the element. When two or more impedance elements shunting faulty contacts are connected in series with the load across the source, the load still remains deenergized and the source voltage divides between the elements and the load in proportion to their relative impedance values, the major portion of the source voltage dividing between the impedance elements for application individually to the faulty contacts to break down the foreign matter separating such contacts.

Where the source 10 supplies alternating current as shown in the preferred apparatus of Figs. 1 to 3, each of the impedance elements 15 and 16 may be a resistor, a capacitor, or an inductor having an effective impedance equal to several times that of the load 11. In the present instance, the elements are resistors of equal value, these being two resistors one connected in shunt around each of only two of the switches. The source 10 is shown as the secondary winding of a transformer whose primary winding is connected across suitable supply lines (not shown).

Under one operating condition in which the contacts of the unshunted switch 14 are separated only by foreign matter and the shunted switches 12 and 13 are open and closed respectively as shown in Fig. 1, no current flows in the circuit and the full voltage of the source is applied across the unshunted contacts through the load, the closed one 13 of the shunted switches, and the resistor 15 shunting the open switch 12. This voltage then is available to break down the foreign matter on the contacts and permit the latter to close.

Should the unshunted switch 14 and one shunted switch 12 be closed with the contacts of the other shunted switch 13 separated only by foreign matter as illustrated in Fig. 2, a small current flows in the circuit and the full voltage of the source is applied across the load 11 and the resistor 16 in series. The voltage across the resistor under this condition is equal substantially to the source voltage due to the relative impedance values of the resistor and the load to break down the foreign matter on the contacts of the faulty switch 13. A similar action occurs if the contacts of the other shunted switch 12 are separated only by foreign matter and the other switches 13 and 14 are closed. If the unshunted switch 14 is closed and the contacts of both shunted switches are separated by foreign matter as shown in Fig. 3, substantially all of the voltage of the source is divided equally between the resistors for application of a part of such voltage individually across each set of faulty contacts.

Where the voltage source 10 supplies direct current as shown in Fig. 4, the impedance elements may be resistors as in the preferred construction described above or may be capacitors 17 and 18, one connected in shunt around each of two of the three switches 12, 13 and 14. The use of capacitors in a direct current circuit is possible because of the characteristic of a capacitor that it acts as a short circuit when in an uncharged condition. Thus, when all three of the switches are separated by foreign matter as shown in Fig. 4, the capacitors, acting as short circuits around the switches 12 and 13, complete a conductive path from the source and through the load to the unshunted contacts to apply the full voltage of the load to these contacts. Upon closure of the unshunted contacts 14, the source voltage then is applied to the two capacitors 17 and 18 in series and divides between the latter in inverse proportion to their capacitance values. Where, as in the

present instance, the values are equal, the source voltage divides equally between the capacitors 17 and 18 for application individually across the open contacts 12 and 13. It will be apparent that the operation of the modified circuit of Fig. 4 is similar to that of the preferred construction under the different conditions described above.

In one control circuit embodying the invention and having a load comprising two parallel relay coils with an energized impedance of approximately 288 ohms connected in series with five sets of switch contacts across an alternating current source of 115 volts, faulty operation of the switch contacts was avoided by connecting a resistor of 10,000 ohms across each of four of the switches. Prior to the use of such shunting resistors, the circuit frequently failed to operate requiring shutdown of the apparatus and cleaning of the contacts of all of the switches.

I claim as my invention:

1. In combination with a device adapted to be energized by the flow therethrough of electric current and means including two sets of switch contacts connected in series with each other and said device for applying to the latter a voltage of a value sufficient to energize the device when both sets of contacts are closed, a resistor connected in shunt around a first one of said sets of contacts and in series with the second set and having a resistance sufficiently higher in value than the impedance of said device to limit current flow through the device to a value insufficient to energize the device and to produce a voltage drop across said first set of contacts substantially equal to the voltage of said source when said first contacts are separated by foreign matter and said second contacts are closed for application of said voltage to the device and said resistor in series, said resistor completing a conductive path through said device for application of said voltage across said second contacts when the contacts of both of said sets are held in open condition by foreign matter thereon.

2. In combination with a device adapted to be energized by the flow therethrough of electric current of a predetermined value and means including two sets of switch contacts connected in series with each other and said device for applying to the device a voltage of a value sufficient to energize the same at said current value when both sets of contacts are closed, two capacitors one connected in a shunt around each of said sets of contacts and each having an impedance sufficiently higher in value than that of said device to limit current flow through the device to a value less than said predetermined value and to produce across the contacts shunted by the capacitor a voltage drop substantially equal to the voltage of said source when such shunted contacts are separated by foreign matter and the other contacts are closed, substantially all of said applied voltage dividing between said capacitors for application of the voltage across each capacitor individually to its shunted contacts to breakdown the foreign matter thereon when the contacts of both sets are separated by such matter.

3. In combination with a device adapted to be energized by the flow therethrough of electric current of a predetermined value and means including two sets of switch contacts connected in series with each other and said device for applying to the device a voltage of a value sufficient to energize the same at said current value when both sets of contacts are closed, a capacitor connected in a shunt around one of said sets of contacts and having an impedance to current flow correlated with such impedance of said device to limit current flow through the latter to a value less than said predetermined value and to produce across the contacts shunted by the capacitor a voltage drop substantially equal to the voltage of said source when such shunted contacts are separated by

foreign matter and the other contacts are closed, said capacitor completing a circuit through said device for application of said voltage across said other contacts when the contacts of both of said sets are held in open condition by foreign matter thereon.

4. In combination with a device adapted to be energized by the flow therethrough of electric current and means including two sets of switch contacts connected in series with each other and said device for applying to the latter a voltage of a value sufficient to energize the device when both sets of contacts are closed, an impedance element connected in shunt around a first one of said sets of contacts and in series with the other set and having an impedance sufficiently higher in value than the impedance of said device to limit current flow through the device to a value insufficient to energize the device and to produce a voltage drop across said first set of contacts substantially equal to the voltage of said source when said first contacts are separated by foreign matter and said second contacts are closed for application of said voltage to the device and said element in series, said impedance element completing a conductive path through said device for application of said voltage across said second contacts when the contacts of both of said sets are held in open condition by foreign matter thereon.

5. In combination with a device adapted to be energized by the flow therethrough of electric current of a predetermined value and means including more than one set of switch contacts connected in series with each other and said device for applying to the latter a voltage sufficient to energize the device when all of the contacts are closed, individual shunting means for at least all except one of said sets of contacts comprising impedance elements each having a value substantially higher than the impedance of said device to limit current flow through the latter to a value less than said predetermined value and to produce a voltage drop across the element equal approximately to the full voltage of said source when the element and the device are connected in series across the source, said voltage drop being applied across the set of contacts shunted by the element to breakdown foreign matter separating the contacts.

6. In combination with a device adapted to be energized by the flow therethrough of electric current of a predetermined value and means including more than one set of switch contacts connected in series with each other and said device for applying to the latter a voltage sufficient to energize the device when all of the contacts are closed, individual shunting means for at least all except one of said sets of contacts comprising impedance elements each having impedance characteristics correlated with such characteristics of said load to limit current flow through the latter to a value less than said predetermined value and to produce a voltage drop across the element equal substantially to full voltage of said source when the element and the device are connected in series across the source, such voltage drop being applied across the set of contacts shunted by the element to break down foreign matter separating the contacts.
